UNITED STATES PATENT OFFICE.

EMMETT W. STULL, OF NORWOOD, OHIO, ASSIGNOR TO ALLIS-CHALMERS COMPANY, A CORPORATION OF NEW JERSEY, AND THE BULLOCK ELECTRIC MANUFACTURING COMPANY A CORPORATION OF OHIO.

CONTROLLER CONSTRUCTION.

No. 903,338.

Specification of Letters Patent.

Patented Nov. 10, 1908.

Application filed March 31, 1906. Serial No. 309,028.

To all whom it may concern:

Be it known that I, EMMETT W. STULL, citizen of the United States, residing at Norwood, in the county of Hamilton and State of Ohio, have invented certain new and useful Improvements in Controller Construction, of which the following is a full, clear, and exact specification.

My invention relates to controllers for electric motors and especially to motor controllers for electric railway cars.

One object of my invention is to greatly reduce or entirely eliminate the sparking at the contacts of the controller, and thereby prevent damage to, or perhaps even the destruction of, the controller or the motors connected thereto.

Another object of my invention is to obtain better engagement between the contact fingers and contact segments of the controller.

Broadly, my invention consists of the combination with a controlling drum, of contact fingers coöperating with the drum, and a blowout magnet having the contact fingers for pole-pieces.

More specifically considered, the invention comprises a controller drum having a paramagnetic shaft, a blowout magnet, the core of which extends beyond its windings, paramagnetic contact fingers with a lining of highly conductive material coöperating with the controller drum and mounted on the extended core of the blowout magnet, thus forming pole-pieces of one polarity for the blowout magnet, the controller shaft forming part of the return magnetic circuit thereof.

Other features of my invention will more clearly appear in the following description and accompanying drawings, and will be specifically pointed out in the appended claims.

Figure 1 is an elevation of a simple form of controller, with the front part of the casing removed, showing my invention applied thereto, and with the controller drum shown partly in section. Fig. 2 is a section on the line 2—2 of Fig. 1; and, Fig. 3 is a detail of one of the contact fingers.

In the drawings, A is the back part of a controller casing, provided with bearings B, B' for the shaft C of the controller drum which has the usual handle C' and notch plate C". Surrounding the shaft is a layer of

insulation D. Spaced from the insulation by collars E is a tube or tubes F to which are fastened as by screws the brass spiders for the copper or other highly conductive contact segments G. The parts A, B, B', C, E, and F are all of iron or other paramagnetic material. Thus the tubes F, save for the insulation D, are practically magnetically continuous with the shaft C, and the latter is magnetically continuous with the casing A. Insulating washers F' are placed at the top and bottom of the drum.

While each contact segment is shown as mounted on a separate spider, the spiders being connected only through the tube F, it is obvious that all the spiders for the same section of the drum might be directly connected together as by being integral.

Integral or otherwise magnetically continuous with the back of the casing A is the core H of the blowout coil I, which may be connected in any desired manner, the connections of the controller and of the blowout coil forming no part of my present invention. Fastened at its lower end to the core H, as by means of screws, so as to be magnetically continuous therewith, and supported at its upper end by a block K of wood or other non-magnetic material, is an iron or other paramagnetic extension L of the core H of the blowout magnet. This extension L serves not only as a path for the magnetic flux, but also as a support for the contact fingers M, which are adjustably attached to the extension L, as by the split iron collars N. These collars are preferably insulated from the extension L of the blow-out magnet core.

The contact fingers M are each made of a strip O of spring steel, iron or other magnetic material having a high permeability, backed or lined by another strip P of highly conductive material such as copper so as to make the fingers better conductors. To the end of each finger may be riveted a copper button Q. The strips O of the contact fingers form pole-pieces of one polarity for the blowout magnet, the controller shaft C and the tube F forming part of the return magnetic circuit thereof.

The path of the flux from the blowout magnet is from the core H, along extension L, to the collars N and pole-pieces or contact fingers M, across the air gap in which the breaking of the circuit takes place, to tube F,

by collars E to shaft C, bearings B, B', casing A, to core H. In order to prevent magnetic leakage, the cover A' and base A² may be of brass or other non-magnetic material. The 5 magnetic attraction between the fingers M and the shaft C and tube F, serves also to cause a firmer contact between the fingers M and the segments G, thus assisting the spring action of the fingers themselves. This magnetic 10 attraction increases with the strength of the current through the blowout coil, and therefore the greater the current through the coil and fingers the firmer the engagement between fingers M and segments G.

15 I have described my invention in what I now consider to be its preferred form, but I do not wish to limit myself to the exact structure shown and described, and therefore I shall claim broadly the novel features invented 20 by me.

I claim as new:—

1. In a controller, a controlling drum, a blowout magnet, and contact fingers formed of a spring strip of magnetic material and a 25 strip of good conducting material mounted on the core of said blowout magnet and cooperating with said drum, said fingers forming pole-pieces for said blow-out magnet.
2. In a controller, a controlling drum having 30 a paramagnetic shaft, a blowout magnet having its core extension beyond its windings, and paramagnetic contact fingers lined with highly conductive material mounted on but

insulated from said core extension, said fingers serving as pole-pieces of one polarity for 35 the blowout magnet, and said shaft forming part of the return magnetic circuit thereof.

3. In a controller, a blow-out magnet, a cylinder carrying drum contacts, and a shaft supporting said cylinder but insulated therefrom, said shaft and cylinder being of magnetic material and forming part of the magnetic circuit of said blow-out magnet.

4. In a controller, a blow-out magnet, a hollow cylinder carrying drum contacts, a 45 shaft extending axially through said cylinder, and one or more collars between said shaft and cylinder, said shaft, cylinder and collars being all of magnetic material and forming part of the magnetic circuit of said 50 blow-out magnet.

5. In a controller, a blow-out magnet, a hollow iron cylinder carrying drum contacts, an iron shaft extending axially through said cylinder, and one or more iron collars supported by but insulated from said shaft and supporting said cylinder, said cylinder, shaft and collars forming part of the magnetic circuit of said blow-out magnet.

In testimony whereof I affix my signature, 60 in the presence of two witnesses.

EMMETT W. STULL.
